UNITED STATES PATENT OFFICE.

WARREN E. WARNER, OF SYRACUSE, NEW YORK, ASSIGNOR TO E. C. STEARNS & CO., OF SAME PLACE.

DOOR-HANGER.

SPECIFICATION forming part of Letters Patent No. 311,697, dated February 3, 1885.

Application filed August 13, 1884. (No model.)

To all whom it may concern:

Be it known that I, WARREN E. WARNER, of the city of Syracuse, in the county of Onondaga and State of New York, have invented 5 new and useful Improvements in Door-Hangers, of which the following is a specification.

This invention relates to an improvement in that class of door-hangers which are employed for supporting sliding doors from the 10 top, and which consists of rollers or wheels which run on horizontal rails, and on which the door is supported by suitable bearings.

The object of my invention is to so construct the hanger that it can be easily applied to the 15 upper edge of the door after the hanger has been placed upon the rails, and without requiring any cutting of the door or fitting to secure it in place, and that it is simple in construction.

20 My invention consists, to this end, of the particular construction of the hanger, which will be hereinafter fully described, and pointed out in the claims.

In the accompanying drawings, Figure 1 is 25 a side elevation, and Fig. 2 an end elevation, of a door-hanger provided with my improvement and secured to the upper edge of a door. Fig. 3 is a longitudinal section on an enlarged 30 scale of the lower portion of the hanger and the upper edge of a door. Fig. 4 is a vertical cross-section in line x x , Fig. 3. Fig. 5 is a top plan view of the horizontal base-plate. Fig. 6 is an end view thereof. Fig. 7 is a perspective view of the sliding plate, which is 35 secured to the base-plate, and which supports the rider-bar.

Like letters of reference refer to like parts in the several figures.

A represents the upper portion of a sliding 40 door, and B B the horizontal rails arranged above the door in the usual manner.

C C are the wheels or rollers of the hanger, which are secured to a shaft, c , at the proper distance apart to run upon the rails B B.

45 D represents a horizontal base-plate, which is secured to the upper edge of the door A by screws d . The plate D consists of a rectangular frame, preferably made of cast or malleable iron, having a flat bottom, which rests

upon the top edge of the door and is provided 50 with screw-holes d' , to receive the screws d .

e are longitudinal ribs formed on the top or face of the plate D on opposite sides of the center of the plate, and provided with raised lugs or projections e' . The inner faces of the 55 lugs e' are inclined from their upper edge downwardly and outwardly to the base of the plate, and form a longitudinal dovetail recess or groove, f , between the two opposite lugs.

g are openings formed in the plate D, between the lugs e' on one side of the plate and the lugs e' on the opposite side of the plate. By cutting away the metal in the plate between two opposite lugs, the latter can be 65 readily cast on the plate without requiring any cores.

h represents a lug or stop formed near one end of the plate opposite the groove f , and i represents a semicircular groove formed on the opposite end of the plate, and arranged 70 lengthwise of the plate and in line with the groove f and stop h . The groove i is provided with a screw-thread, j , in which is arranged a horizontal screw-bolt, J .

K represents the vertical plate or frame of 75 the hanger, which supports the rider-bar and friction-roller. The plate K is provided at its lower edge with inclined ledges or ribs k , which project from opposite sides of the plate, and which are adapted to engage between the 80 ears e' of the base-plate D.

L represents the rider-bar, which rests on the axle c between the rollers C C.

M represents a horizontal lever, pivoted at its center to the vertical frame or plate K, and 85 at one end to the downwardly-projecting arm l of the rider-bar L. The opposite end of the lever M is provided with a slotted jaw, m , in which is arranged a screw-nut, n .

o represents an inclined slotted lug formed 90 at the front end of the frame K, and P is a screw-bolt which extends from the lug o through the screw-nut n , and engages with its upper end in a threaded socket, q , formed on the arm l' of the rider-bar. The screw-bolt P 95 is provided with a right and left hand screw-thread, p' p'' , which engages, respectively, with the screw-nut n and threaded socket q . The

screw-bolt P is provided with a notched head, r, and a collar, r', and the jaws of the lug o straddle the bolt P between the head r and collar r'. By this means the bolt P is prevented from moving longitudinally in the lug o, but is free to turn therein. The screw-nut n is confined between the slotted jaw m of the lever M by flat grooves n', formed on opposite sides of the nut. The nut is prevented from turning in the jaw m by the flat sides of the nut n bearing against the sides of the jaw. By turning the screw-bolt P in one or the other direction the lever M is caused to swing on its central pivot and the rider-bar is adjusted. 15 The portion of the door to which the hanger is attached can thus be readily raised or lowered, as may be necessary, to level or adjust the door. The hanger may be provided with any other suitable adjusting device, whereby 20 the door can be adjusted and leveled. The plate K is provided with a vertical pin or spindle, s, on which is mounted a friction-roller, S. The roller S is so arranged as to run between the rails B B and retain the wheels C C upon 25 the rails.

In applying my improved hanger to the upper edge of a door the horizontal base-plate D is removed from the hanger-frame, and is firmly secured to the top of the door by the screws d. 30 The hanger is inserted through an opening formed in the rails, so that the rollers will rest upon the rails, and the frame or plate K will be suspended below the rails. The door, with the plate D fastened thereto, is then arranged 35 in place, and the hanger-frame is secured to the base-plate by sliding the base of the plate K in the groove or recess f of the horizontal plate D until the inclined ribs k engage under the projecting lugs e' e' and the rear end of the 40 plate K comes in contact with the stop h. The bolt J is then inserted in the groove i, in the

front end of the plate, and engaged with the screw-thread j until the threaded end of the bolt bears against a lug, j', formed on the front of the plate K, whereby the latter is firmly fastened to the horizontal base-plate and the hanger secured to the door. 45

By forming the horizontal base-plate in a separate piece from the hanger-frame the hanger can be readily and easily secured to the 50 door after the hanger has been placed in position upon the rails.

By constructing the base-plate as described the latter can be readily and cheaply made of malleable or cast iron, and is secured to the 55 upper edge of the door without cutting the door or requiring any fitting to secure it in place.

I am aware of the pending application of Obadiah Seely, filed August 2, 1884, Serial No. 139,475, and do not desire to claim the improvements in the rider-bar, its adjusting device, and friction-roller claimed therein. 60

I claim as my invention—

1. The combination, in a door-hanger, of a base-plate, D, provided with projecting lugs 65 e', having overlapping inner faces, a stop, h, a longitudinal groove, i, provided with a screw-thread, j, and a screw, J, substantially as set forth.

2. In a door-hanger, the combination, with 70 the base-plate D, provided with lugs e'; a central longitudinal groove, f, stop h, and recess i, provided with a screw-thread, j, of a plate, K, provided with ribs k, and a screw, J, engaging in the screw-thread of the groove i and 75 bearing against the plate K, substantially as set forth.

Witness my hand this 31st day of July, 1884.

WARREN E. WARNER.
